UNITED STATES PATENT OFFICE

EDWARD P. ESCHER, OF DETROIT, MICHIGAN, ASSIGNOR TO STEPHENS-ADAMSON MFG. CO., OF AURORA, ILLINOIS, A CORPORATION OF ILLINOIS

DEVICE FOR DEWATERING SAND AND GRAVEL

Application filed February 9, 1927. Serial No. 166,964.

This invention relates to a settling basin provided with a device for dewatering sand and gravel pumped therein by a dredge.

The principal object of the invention is the provision of new and improved settling basin provided with means whereby sand and gravel pumped therein admixed with water may be dewatered easily and with facility.

Another object of the invention is the provision of a new and improved settling basin so constructed that the sand and gravel pumped into the same may be slid along its bottom wall to a point above the water level within said basin.

15 A further object of the invention is the provision of a new and improved settling tank having an inclined bottom wall terminating at its upper end in a draining table for receiving the wet sand and gravel from 20 said tank.

A still further object of the invention is the provision of a new and improved combined settling basin and hoppers together with means for transporting the super-saturated sand or gravel from said basin and dewatering it before depositing the same in said hoppers.

Other objects of the invention are the provision of a new and improved settling basin 30 and dewatering device that is simple in construction and that is efficient in operation.

Other and further objects and advantages of the invention will appear from the following description taken in connection with 35 the accompanying drawings, in which

Fig. 1 is a plan view of the device;

Fig. 2 is a section on line 2—2 of Fig. 1;

Fig. 3 is a section on line 3—3 of Fig. 1; and

40 Fig. 4 is a section on line 4—4 of Fig. 1.

A very large amount of the sand and gravel used in construction work is obtained from sand and gravel beds below rivers, lakes and other bodies of water. The sand and gravel, usually dredged and mixed with water, is transported in a fluid state to settling basins through suitable pipes. The sand and gravel settles to the bottom of the basin and is removed and transported to the screening de-

55 It is common practice to employ the common endless chain and bucket conveyer for removing the sand from the settling basin, but the mechanism is more or less complicated and is expensive to operate. It has also been proposed to employ a pair of settling tanks whereby the sand may be removed from one while the sand and gravel are being pumped into the other. But this method is 60 cumbersome and undesirable.

The present invention seeks to eliminate these difficulties by the provision of a basin and simple mechanism for removing the sand and gravel, draining the same, and depositing the material in a hopper in a fairly dewatered 65 condition.

In the form of the device selected to illustrate one embodiment of the invention, the numeral 10 designates a settling basin having what will be termed the front end wall 11, 70 and the side walls 12 and 13. The bottom wall 14 of the basin is inclined upwardly and rearwardly as shown in Fig. 2 to form a slide-way 15. The slideway 15 is extended as at 16 and its central portion is slightly elevated and 75 crowned to form a draining or dewatering table 17, see Fig. 4, the gutters or channels 18 and 19 at each side thereof.

One or more hoppers 21 are provided at the upper end of the table 17 for receiving 80 the sand and gravel dragged upwardly along said table, as will presently appear. The number of hoppers employed will depend on whether one or more dump cars are employed on the elevator mechanism. As shown, two 85 hoppers are employed. These hoppers have their common partition 22 provided in the form of an inverted V on the centerline of the basin for dividing the loads of sand and gravel for the two hoppers.

90 Each hopper is provided with a discharge opening 23 located in a pit 24, as shown in Figs. 2 and 3. Valves 25 operated in any suitable manner, as by means of the compressed air operating device 26, are provided for 95 controlling the discharge of the sand and gravel into the dump cars or skip bucket 27, which carry the same up the incline tracks 28 to the screening mechanism in the usual manner.

The side walls 12 and 13 of the tank or basin 10 are preferably extended rearwardly about the hoppers and are provided in their intermediate portion with overflow ports 29 whereby the water level will remain below the dewatering table 17 as clearly shown in Fig. 1.

The tank or basin is deeper at its forward end and the mixture of sand, gravel and water is pumped into said tank or basin by the dredge through the pipe 31 in the usual or any well known manner, and settles to the bottom of said tank, the excess water overflowing through the over flow ports 29.

Suitable means are provided for dragging the sand or gravel up the inclined slideway or bottom of the tank onto the draining or dewatering table 17. In the form of the device shown, which is by way of example only, a drag scraper or scraper bucket 32 of any approved construction, is employed for this purpose. A haul cable 33 which extends around the pulleys 34 and 35 and to the station 36, is adapted to draw the drag scraper 32 across the sand 37 in the basin, thereby filling said scraper and moving the load up the inclined slideway onto the table 17. A pull-back or return cable 38 which extends around the pulleys 39 and 41 and to the station 36 is adapted to return the scraper. Preferably the pulleys 34 and 39 are of the longitudinal centerline of the basin whereby the sand will be deposited by the scraper on the central portion of the dewatering table 17.

The basin or tank 10 may be of any convenient size and shape so long as it has an inclined bottom or slideway along which the drag scraper loaded with sand may slide. For large screening plants the tank is very large in dimension, but its size will depend upon the capacity of output desired.

In the operation of the device the material which for convenience of description will be termed sand, whether it be sand or gravel or both, is pumped into the tank in the usual manner. The scraper is moved by the cable 33 across the material and up the inclined bottom wall of the tank onto the dewatering table 17 to a point adjacent to the hoppers, where the load 42 is left and the scraper returned by the cable 38. The water in the sand of the load 42 will drain onto the table 17 and flow into the gutters 18 and 19, back into the tank 10, while the scraper is being returned for the next load. The succeeding load of the scraper will push the preceding load which is fairly dewatered, forwardly onto the hoppers. If desired, the scraper load may be deposited directly onto the hoppers, but preferably it is left on the dewatering table during the time it takes to deliver the succeeding load.

The operation of the dredge and dewatering device may be simultaneous and continuous.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In combination, a settling basin for receiving a mixture of water and particles of solid material from a dredge, an inclined slideway formed in the bottom of said basin, said inclined slideway having its side edges lower than its central portion, a scraper and means for drawing said scraper across said material deposited in said basin and up said slideway above the water line in said basin. 75

2. In combination, a basin having an inclined bottom wall with the upper surface of its upper portion convex, a scraper member and means for drawing said scraper or bucket upwardly along said inclined bottom wall. 85

3. In combination, a basin having side walls, an inclined bottom and end wall, said walls extending above the water line in said basin, a scraper, means for drawing said scraper across said basin for loading the same with sand deposited in said basin, said means being adapted to draw said loaded scraper up said inclined wall, and means for withdrawing said scraper and leaving said sand on said inclined wall above said water line. 95

4. A settling tank for receiving sand, gravel and the like pumped from a deposit by a dredge, an inclined slideway in said tank terminating in a crowned dewatering table above the normal level of the water in said tank. 100

5. In combination, a settling tank, a conduit for conducting sand and water to said tank, an inclined slideway in said tank, the upper portion of said slideway being above the normal water line in said tank, a drag scraper of materially less width than said slideway, means for reciprocating said scraper longitudinally of said tank for dragging the sand along said slideway above the water line of said tank, and means for causing water to drain laterally from said sand when the same has been deposited on said slideway. 110

6. In combination, a settling tank for receiving sand, gravel, water and the like pumped into the same by a dredge, a hopper adjacent to said tank, an inclined slideway, extending from said hopper to said tank and constituting the bottom wall of said tank, said slideway being crowned in its central portion and provided with gutters at the sides thereof. 120

7. A settling basin comprising sides and one end wall only, discharge ports in one of said side walls above the bottom thereof, the 130

bottom wall of said basin being inclined upwardly and terminating above the level of the lower edge of said ports whereby the upper end of said bottom wall will constitute a draining table, the outer side portions of said table being lower than the central portions thereof for constituting gutters.

5 In testimony whereof I affix my signature.
EDWARD P. ESCHER.
